(57) **CLAIM**

The ornamental design for a stool with two seating surfaces, as shown and described.

DESCRIPTION

FIG. 1 is an upper front perspective view of the stool with two seating surfaces showing the new design;

FIG. 2 is a front view thereof;

FIG. 3 is a back view thereof;

FIG. 4 is a side view thereof, with the opposing side view being a mirror image;

FIG. 5 is a top view thereof;

FIG. 6 is a bottom view thereof;

FIG. 7 is an upper rear perspective view thereof showing the stool oriented for a person to sit on a first seating surface on the top of the stool;

FIG. 8 is an upper side perspective view thereof showing the stool oriented for a person to sit on a second seating surface on the front of the stool;

FIG. 9 is an upper front perspective view of the stool showing how the stool can be stacked; and,

FIG. 10 is an upper front perspective view of the stool showing broken lines on the top and front of the stool depicting an optional pad.

The evenly dashed broken lines in all figures illustrate portions of the stool not forming no part of the claimed design. The long dash/short dash broken lines shown in FIG. 9 depict environmental subject matter, specifically additional instances of the stool, and form no part of the claimed design.
